[57] CLAIM

The ornamental design for a high intensity discharge light fixture, as shown and described.

DESCRIPTION

FIG. 1 is a front isometric view of a high intensity discharge light fixture showing our new design;
FIG. 2 is a front elevational view thereof on an enlarged scale;

FIG. 3 is a top plan view thereof on an enlarged scale;
FIG. 4 is a side elevational view thereof on an enlarged scale, the opposite side being substantially identical;
FIG. 5 is a bottom plan view thereof on an enlarged scale;

FIG. 6 is a rear elevational view thereof on an enlarged scale.

FIG.1

FIG. 2

FIG. 3

FIG. 4

FIG. 5

FIG. 6
